UNITED STATES PATENT OFFICE

135,378

DESIGN FOR A POCKET STEREOSCOPE

Bernard Chadkin, New York, N. Y.

Application December 28, 1942, Serial No. 109,155

Term of patent 7 years

To all whom it may concern:

Be it known that I, Bernard Chadkin, a citizen of the United States, residing in the city of New York, county and State of New York, have invented a new, original, and ornamental Design for a Pocket Stereoscope, of which the following is a specification, reference being had to the accompanying drawing, forming part thereof, and in which:

Figure 1 is a front elevational view of a pocket stereoscope, showing my new design.

Figure 2 is a top plan view of the same; while Figure 3 is an end view in elevation thereof; and

Figure 4 is a bottom plan view, showing the pocket stereoscope in folded position.

I claim:

The ornamental design for a pocket stereoscope, substantially as shown.

BERNARD CHADKIN.
